UNITED STATES PATENT OFFICE

RICHARD K. HOHMANN, OF BROOKLYN, NEW YORK, ASSIGNOR TO FREDERICK OSANN COMPANY, OF NEW YORK, N. Y., A CORPORATION OF NEW YORK

SEWING MACHINE

Application filed January 24, 1928. Serial No. 248,992.

My invention relates to sewing machines of the rotary shuttle type in which the shuttle is mounted for rotation or oscillation in a race-way formed within a suitable frame or casement at the under side of the sewing machine bed-plate. Such casement is usually formed with an opening intersecting the race-way for the passage of the needle in its reciprocations and to permit of the thread loop 5 thrown out by the needle to be engaged by the shuttle point in the stitch forming operation. When the thread loop is engaged by the shuttle point, it is carried by the latter around the bobbin contained within the shuttle so as 10 to interlock with the under or bobbin thread in the formation of a stitch in well known manner. In the normal operation of the machine, including the proper tensioning of the thread, the needle-thread loop is carried about 15 the shuttle and contained bobbin without undue obstruction by or interference with any of the adjacent or associated parts, but in the event of breakage of the thread, or of the loose end being drawn beneath the work at the 20 commencement of the sewing operation, or of the thread being unduly slack through im- 25 proper tensioning or other cause, it is liable to be drawn into the race-way by the shuttle and so interfere with the stitching operation; 30 the thread under some of these circumstances becoming so tightly wedged between the shuttle and race-way wall as to necessitate the removal of the shuttle from its race-way preliminary to continuing the sewing operation. 35 With the foregoing in mind, it has been the object of my present invention to provide a simple and efficient means for so controlling the thread during its initial engagement by the shuttle in the space between the needle 40 and the mouth of the raceway as to prevent its being drawn into the latter. This object I accomplish, in a preferred form of my invention, by the provision of a thread guide 45 formed and positioned to enter the needle thread loop as it is carried forward by the shuttle and deflect the sides thereof laterally beyond the sides of the race-way at its mouth, whereby the thread will be prevented from 50 entering or being drawn into the latter.

Referring now to the accompanying drawings—

Fig. 1 is a front end elevation of a portion of a sewing machine equipped with my invention; the feed device being omitted for the 55 better showing of the adjacent parts;

Fig. 2 is a plan view from the upper side of the bed plate, with the needle or throat plate removed, showing the needle-thread loop engaged by the thread guide for deflection 60 thereby to opposite sides of the mouth of the shuttle race-way;

Fig. 3 is a view similar to Fig. 1, with the shuttle shown at a different point in its rotation;

Fig. 4 is a section on line 4—4 of Fig. 3, but with the shuttle removed from its race-way to better show the position of the thread guide relative to the mouth of the race-way. In this 70 view the needle or throat plate is also removed.

Fig. 5 is a detail, in perspective, showing the thread loop engaged by the shuttle point just subsequent to its throw out by the needle and with the point of the thread guide entering said loop.

The sewing machine herein illustrated as equipped with my invention is the well known "Standard" rotary shuttle machine, and comprises the bed-plate 1, the reciprocating needle 2, the rotary shuttle 3 with its peripheral guide flange 4, the frame or casement 5 with its circular race-way 6 in which the guide flange 4 of the shuttle is seated for the support and guidance of the shuttle 80 in its operation, and the bobbin-case 7 mounted within the shuttle on the central stud or spindle 8 therein; these several parts being of usual construction and operation.

The casement 5 is provided at its upper side with a transversely arranged opening 10 intersecting the shuttle raceway, which opening ordinarily termed the "needle opening", provides space for the passage of the needle in its reciprocations and also for the throwing out of the thread loop by said needle in position to be engaged by the shuttle.

In the operation of the machine, the needle, in its ascent, throws out a thread loop *t* 100

which is engaged by the point 12 of the shuttle and carried thereby around the bobbin to its point of cast-off, where it is drawn up by the take-up (not shown) into interlocking engagement with the bobbin-thread in usual manner. In the normal or proper operation of the machine, the thread loop, upon its engagement by the shuttle, is carried thereby in a path which extends below the mouth or entrance 14 of the race-way, as shown in Figs. 1 and 2, whereby any possibility of the thread becoming drawn into the race-way at such point is avoided. As hereinbefore stated, however, if the loose end of the thread becomes drawn beneath the work at the commencement of the stitching operation, or the thread becomes unduly slack or broken, it is liable to be drawn into the mouth of the race-way by the advancing shuttle point 12 and so clog the race-way as to prevent the proper operation of the shuttle and consequently of the machine. To avoid possibility of this, I provide a guide member 15, preferably in the form of a wedge, which is positioned with its wide or base end above and adjacent the mouth of the race-way, and with its point projecting rearwardly towards the path of the needle in position to enter the thread loop as the latter is carried forward by the shuttle, as shown. The base end of the guide 15 is of somewhat greater width than the mouth 14 of the race-way so as to extend laterally beyond each side thereof, as best shown in Figs. 2 and 4, whereby the sides of the thread loop or any loose end thereof engaged by the guide will be deflected laterally beyond the sides of the race-way before reaching the mouth thereof and so be prevented from being drawn into the latter. The guide or deflector 15 thus constitutes a very simple and effective means for avoiding clogging of the shuttle race-way by the thread, by preventing possibility of the thread becoming drawn into the said race-way.

45 The device 15 may be supported in position in any suitable or desired way. As here shown, it is provided with an attaching shank 16 by means of which it is removably secured on the upper side of the race-way casement by a fastening screw 17.

What I claim is:

1. In a rotary shuttle sewing machine, the combination with the stitching mechanism comprising a reciprocating needle, a rotary shuttle, and a casement having a circular race-way in which the shuttle is supported for operation, said casement having an opening intersecting its race-way for the passage of the needle, and the front wall of said opening containing the mouth of the race-way being spaced substantially in advance of the path of the needle, of a thread guide formed and positioned to enter the needle thread loop as it is carried forward by the shuttle and deflect the sides thereof laterally beyond the

sides of the race-way before reaching the mouth of the latter, for the purpose set forth.

2. In a rotary shuttle sewing machine, the combination with the stitching mechanism comprising a reciprocating needle, a rotary shuttle, and a casement having a circular race-way in which the shuttle is supported for operation, said casement having an opening intersecting its race-way for the passage of the needle and the front wall of said opening containing the mouth of the race-way being spaced substantially in advance of the path of the needle, of a wedge-shaped thread guide positioned to enter the needle thread loop as it is carried forward by the shuttle and deflect the sides thereof laterally beyond the sides of the race-way before reaching the mouth of the latter, for the purpose set forth.

3. In a rotary shuttle sewing machine, the combination with the stitching mechanism comprising a reciprocating needle, a rotary shuttle, and a casement having a circular race-way in which the shuttle is supported for operation, said casement having an opening intersecting its race-way for the passage of the needle and the front wall of said opening containing the mouth of the race-way being spaced substantially in advance of the path of the needle, of a thread guide extending from the mouth of the race-way towards the path of the needle and formed to enter the needle thread loop as it is carried forward by the shuttle and deflect the sides thereof laterally beyond the sides of the race-way before reaching the mouth of the latter, for the purpose set forth.

4. In a rotary shuttle sewing machine, the combination with the stitching mechanism comprising a reciprocating needle, a rotary shuttle, and a casement having a circular race-way in which the shuttle is supported for operation, said casement having an opening intersecting its race-way for the passage of the needle and the front wall of said opening containing the mouth of the race-way being spaced substantially in advance of the path of the needle, of a wedge-shaped thread guide supported on the casement in position extending from the mouth of the race-way towards the path of the needle and operative to enter the needle thread loop as it is carried forward by the shuttle and deflect the sides thereof laterally beyond the sides of the race-way before reaching the mouth of the latter, for the purpose set forth.

5. In a rotary shuttle sewing machine, the combination with the stitching mechanism comprising a reciprocating needle, a rotary shuttle, and a casement having a circular race-way in which the shuttle is supported for operation, said casement having an opening intersecting its race-way for the passage of the needle and the front wall of said opening containing the mouth of the race-way being spaced substantially in advance of the path of the needle, of a thread guide formed and positioned to enter the needle thread loop as it is carried forward by the shuttle and deflect the sides thereof laterally beyond the

of the needle, of a thread guide removably mounted on said casement and formed and positioned to enter the needle thread loop as it is carried forward by the shuttle and deflect the sides thereof laterally beyond the sides of the race-way before reaching the mouth of the latter, for the purpose set forth.

6. In a rotary shuttle sewing machine, the combination with the stitching mechanism comprising a reciprocating needle, a rotary shuttle, and a casement having a circular race-way in which the shuttle is supported for operation, said casement having an opening intersecting its race-way for the passage of the needle and the front wall of said opening containing the mouth of the race-way being spaced substantially in advance of the path of the needle, of a thread guide extending from the mouth of the race-way rearwardly towards the needle and being formed to engage the thread carried forward by the shuttle and deflect the same laterally to either side of the race-way mouth.

7. In a rotary shuttle sewing machine, the combination with the stitching mechanism comprising a reciprocating needle, a rotary shuttle, and a casement having a circular race-way in which the shuttle is supported for operation, said casement having an opening intersecting its race-way for the passage of the needle and the front wall of said opening containing the mouth of the race-way being spaced substantially in advance of the path of the needle, of a thread guide extending from the mouth of the race-way rearwardly towards the needle and being wedge-shaped to engage the thread carried forward by the shuttle and deflect the same laterally to either side of the race-way mouth.

46 In testimony whereof I affix my signature.
RICHARD K. HOHMANN.
